United States Patent Office

Des. 188,485
Patented Aug. 2, 1960

188,485

HINGE

La Verne E. Clayton, Rockford, Ill., assignor to Amerock Corporation, Rockford, Ill., a corporation of Illinois

Filed Apr. 4, 1960, Ser. No. 60,002

Term of patent 14 years

(Cl. D10—9)

Figure 1 is a front elevational view of a hinge showing my new design.

Fig. 2 is a top view.

Fig. 3 is an enlarged sectional view taken along the line 3—3 in Fig. 1.

Fig. 4 is a side view of the hinge.

I claim:

The ornamental design for a hinge, substantially as shown.
